UNITED STATES PATENT OFFICE.

WILLIAM LISLE KEYS, OF OMAHA, NEBRASKA.

DESIGN FOR A REFLECTOR AND BRACKET THEREFOR.

41,989.

Specification for Design.

Patented Dec. 19, 1911.

Application filed August 31, 1911. Serial No. 647,083. Term of patent 7 years.

To all whom it may concern:

Be it known that I, WILLIAM LISLE KEYS, a citizen of the United States, residing at Omaha, in the county of Douglas and State of Nebraska, have invented a new, original, and ornamental Design for a Reflector and Bracket Therefor, of which the following is a specification, reference being had to the accompanying drawing, forming a part thereof.

Figure 1 is a plan view of a reflector and bracket therefor, showing my new design.

Fig. 2 is a side view of the reflector and bracket therefor, and Fig. 3 is a front view of the same.

I claim:

The ornamental design for a reflector and bracket therefor as shown.

In testimony whereof I have affixed my signature in presence of two witnesses.

W. LISLE KEYS.

Witnesses:

HIRAM A. STURGES,
